(57) **CLAIM**

I claim The ornamental design for a wearable optic lens ring, as shown and described.

DESCRIPTION

FIG. 1 is a perspective view of a wearable optic lens ring embodying the design in which the broken lines represent environment and form no part of the claimed design;

FIG. 2 is a front elevational view thereof;

FIG. 3 is a rear elevational view thereof;

FIG. 4 is a sectional view thereof;

FIG. 5 is a top plan view thereof;

FIG. 6 is a bottom plan view thereof;

FIG. 7 is a sectional view thereof;

FIG. 8 is a left side view thereof; and,

FIG. 9 is a right side view thereof.
